US0D1049588S

(12) **United States Design Patent** (10) **Patent No.:** **US D1,049,588 S**
(45) **Date of Patent:** **** Nov. 5, 2024**

(54) **SHOE OUTSOLE BOTTOM**

- (71) Applicant: **Skechers U.S.A., Inc. II**, Manhattan Beach, CA (US)
- (72) Inventor: **Glen Chang**, Rancho Palos Verdes, CA (US)
- (73) Assignee: **Skechers U.S.A., Inc. II**, Manhattan Beach, CA (US)
- (**) Term: **15 Years**
- (21) Appl. No.: **29/926,466**
- (22) Filed: **Jan. 30, 2024**

Related U.S. Application Data

- (62) Division of application No. 29/879,848, filed on Jul. 13, 2023.
- (51) **LOC (14) Cl.** **02-04**
- (52) **U.S. Cl.** USPC **D2/959**; D2/951

(57) **CLAIM**

The ornamental design for a shoe outsole bottom as shown and described.

DESCRIPTION

FIG. 1 is a front perspective view of the shoe outsole bottom in accordance with my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view thereof.

Broken lines shown in the drawing represent portions of the outsole bottom and midsole periphery, and the environmental structure of the upper which form no part of the claimed design.

1 Claim, 8 Drawing Sheets
